UNITED STATES PATENT OFFICE.

JOHN W. OSTRANDER, OF MADISON, WISCONSIN.

HOIST CONSTRUCTION.

Application filed January 31, 1924. Serial No. 689,725.

To all whom it may concern:

Be it known that JOHN W. OSTRANDER, a citizen of the United States, residing at Madison, in the county of Dane and State of Wisconsin, has invented certain new and useful Improvements in Hoist Constructions, of which the following is a specification.

The present invention relates to hoist construction and the main object of the invention is to utilize small sectioned timber in building a hoist and more particularly in using clamping bolts for the timber without boring holes through the same.

Another object of the invention is to construct the hoist so that the angular position may be adjusted in the manner of a so-called "gin pole."

In the accompanying drawings, one embodiment of the invention is illustrated, and Figure 1 is a fragmentary front elevation of the hoist;

Figure 2 is a fragmentary section along line 2—2 of Figure 1;

Figure 3 is a fragmentary section along line 3—3 of Figure 1;

Figure 4 is a cross section along line 4—4 of Figure 1;

Figure 5 is a perspective view of one detail;

Figure 6 is a section along line 6—6 of Figure 4;

Figure 7 is a fragmentary elevation of the top portion of a hoist of heavier construction than shown in the preceding figures;

Figure 8 is a transverse section along line 8—8 of Figure 7, and

Figure 9 is a plan view of a detail.

In Figures 1 to 6 of the drawings is shown a hoist constructed of two uprights or timbers 10 having a cross section preferably two inches by four inches. This is a size that is commonly carried on the market and therefore easily obtained. These uprights are spaced apart by one or more spacing blocks 11 positioned intermediate of the ends, a base block 12 at the lower end of the hoist, and a crown 13 at the top. In this manner a beam is formed of considerable strength.

The base block 12 extends a sufficient distance up between the uprights to form a solid lower end of the beam upon which a winch 14 is secured. This winch is constructed in the usual manner with a drum 15 for the hoisting rope or cable 16, a ratchet

dog and wheel 17, and crank handles 18. The bottom ends of the uprights 10 and the base block 12 are held together by side plates 19 and securing bolts 20, while still other bolts 21 secure the base block or spreader 12 to the plates 19. In the center of the base block 12 is threaded a spindle 21 preferably pinned, as at 22, and forming a pivot for the hoist. This spindle projects below the lower end of the beam and rests on a base block 22 which, for this purpose, is provided with a socket 23. This socket is conical with a wide bottom and a narrow mouth slightly larger than the diameter of the spindle 21 so that the spindle, together with the hoist beam, can rock or swivel in the socket. The free end of the spindle is surrounded by a short piece of pipe 24 and washers 25 and 26 are furnished at each end of the pipe or sleeve 24 upon the spindle 21.

The spacing block 11 as well as the upper end of the base block 12 are secured by a clamping device 27 shown in detail in Figures 4, 5 and 6. The clamping device 27 consists of an L-bolt 28 and two eye bolts 29 and 30, together with an anchor or cross piece 31. As will be noted these bolts are placed around the timbers and do not penetrate the same as is usual in similar constructions. In this manner the timbers are not ruined and can be used for similar or other purposes when the hoist is taken down. The L-bolt 28 has a long and a short shank each engaging in the corresponding ears 32 and 33 of the short eye bolt 29 and the long eye bolt 30, whereby the three bolts engage all four sides of the beam. The ends of the L-bolt are threaded and adapted to receive each a sleeve 34, washers 35, 36, and a nut 37.

The cross piece or anchor 31 is provided with two open-sided channels 38 and 39 adapted to accommodate the two eye bolts 29 and 30. These channels accordingly run at right angles to each other, one being superposed above the other, as best seen in Figures 5 and 6. The cross piece is placed at one corner of the beam in such a manner that the open sides of the channels face inwardly, thereby facilitating the placing of the eye bolts 29 and 30 in the channels as indicated in Figures 4 and 6. The free ends of the eye bolts 29 and 30 are threaded and adapted to each receive a sleeve 40, washer 41 and a nut 42. It will thus be seen that when the nuts 37 and 42 are turned home the bolts 28, 29 and 30 will draw the timbers

2 closely together to form a firm connection. The sleeves 34 and 40 are mainly provided for adjustment so that the same clamping bolts may be used for smaller or larger beam 5 construction.

The crown 13 has a top portion 43, see Figures 1 and 2, covering the upper ends of the uprights 10, and downwardly directed side walls 44 placed on the outer faces there- 10 of and secured thereto by means of securing bolts 45. On the top portion 43 stands a pipe 46 extending upwardly, and adapted to house a suspension rod 47 for the hoisting cable or rope 16 which engages over a 15 pulley block 48 hung in an eye 49 furnished at the lower end of the rod 47. A suitable opening 50 is provided for the rod in the top portion 43.

A guy rope plate 51 preferably square in 20 outline is placed around the rod 47, resting upon the top portion 52 of one of the braces 58 and 60 above the pipe 46. A nut 53 is threaded on the rod 47 to retain the same in position. The four corners of the guy rope 25 plate 51 are turned down to form rounded edges and adjacent to these corners are provided apertures 54 in which the upper ends of guy ropes 55 are secured. It will thus be seen that the rounded edges at the 30 corners will prevent the cutting of the ropes at these places.

Under the nut 53 is furnished a washer 56 and between this washer and the top portion 52 is inserted a short piece of pipe 57 which is slightly longer than the thickness of the guy rope plate 51 so that the nut 53 and the washer 56 do not actually rest upon the guy rope plate 51 but upon the short pipe 57 which transmits the pressure downwardly through the top portion 52 of the brace 58, and through the brace 60 and the pipe 46 to the top portion 43 of the crown. This arrangement is made for the purpose of permitting the guy rope plate 51 to turn 40 around the short pipe 52 and adjust itself to the direction of the guy ropes 55 for which reason the central opening 70 in the plate 51 has a larger diameter than the outside of said pipe 57.

Braces 58 bolted to the sides of the crown, as at 59, extend upwardly terminating with the top 52 through which the rod 47 extends. At right angles to the braces 58 are positioned other braces 60 bolted, as at 61, 55 to the uprights 10. These other braces 60 also extend upwardly and engage around the rod 47.

It is evident that beside the nuts 37, 42 and 53, lock nuts may also be provided on the corresponding bolts 28, 29, 30, and rod 47.

In Figures 7 and 8 is shown a hoist construction for heavier loads in which four beams 63 are shown preferably each con- 65 structed of four corner uprights 64 using

timbers four inches by four inches in cross section and spaced apart by spacing blocks 65. Clamping devices 66 of similar construction as the above described clamping devices 27 are used to firmly connect the up- 70 rights. A crown 67 and plate 68 for the guy ropes 69 are furnished and secured at the top of the hoist in a similar manner as shown in Figs. 1 to 6.

The hoist in accordance with the present 75 invention, whether of the lighter or heavier construction, uses timbers which may be taken down and used for other purposes as, with exception of the ends thereof, no boring of the timbers is needed and they are 80 accordingly undamaged and as good as new.

Referring particularly to Figs. 2 and 3, these show the beam in tilted position and supported by the guy ropes 55 in the manner of a "gin pole." When thus tilted the 85 spindle 21 rests on the bottom of the socket 23 engaging the mouth thereof and it will thus be evident that the beam can be given a considerable inclination in any direction to facilitate the hoisting work to be carried 90 out.

Having thus described the invention, what is claimed as new is:

1. A structural beam composed of a plurality of longitudinal members, spacers between said members, clamping devices bearing against the outer faces of said members and said spacers and encircling the same, said clamping devices being slidably engaged one with another, and means fitted to 95 said devices to effect longitudinal movement of the several devices and bind them around the beam.

2. A structural beam composed of a plurality of longitudinal members, spacers for 100 said members, and clamping devices engaging the outer faces of said members and said spacers and adapted to bind them firmly together; each of said clamping devices including an L-bolt, a pair of eye bolts engaging with said L-bolt, an element adapted to 105 connect said eye bolts, and securing means for said bolts.

3. A structural beam composed of a plurality of longitudinal members, spacers for 110 said members, and clamping devices engaging the outer faces of said members and said spacers and adapted to bind them firmly together; each of said clamping devices including an L-bolt, a pair of eye bolts 115 engaging with said L-bolt, an anchor piece provided with channels adapted to receive said eye bolts, and nuts threaded on the ends of said eye bolts and said L-bolt respectively and adapted to firmly secure the bolts and 120 the anchor piece together around said beam.

4. A structural beam composed of a plurality of longitudinal members, spacers for 125 said members, and clamping devices engaging the outer faces of said members and 130

said spacers and adapted to bind them firmly together; each of said clamping devices including an L-bolt, a pair of eye bolts engaging with said L-bolt, an anchor piece provided with channels adapted to receive said eye bolts, and nuts threaded on the ends of said eye bolts and said L-bolt respectively

and adapted to firmly secure the bolts and the anchor piece together around said beam, said channels being situated at right angles 10 to each other in said anchor piece and opening inwardly as regards the beam.

In testimony whereof I affix my signature.
JOHN W. OSTRANDER. [L.s.]
